UNITED STATES PATENT OFFICE.

CHILION BENJAMIN JOHNS, OF EBENSBURG, PENNSYLVANIA, ASSIGNOR OF ONE-HALF
TO JOSEPH O. CLARK, OF GLEN CAMPBELL, PENNSYLVANIA.

SAND-PIPE HEATER.

Application filed April 28, 1923. Serial No. 635,403.

To all whom it may concern:

Be it known that I, CHILION BENJAMIN JOHNS, a citizen of the United States, residing at Ebensburg, in the county of Cambria and State of Pennsylvania, have invented certain new and useful Improvements in Sand-Pipe Heaters, of which the following is a specification.

This invention relates to sanding devices 10 employed upon railway locomotives, street cars, mine motors, and the like, and has for one of its objects to provide a simply, constructed attachment, whereby the sand pipe is heated and the accumulation of moisture 15 therein prevented, and the free flowing of the sand, provided.

Another object of the invention is to provide a device of this character which may be readily attached to or removed from the 20 sand pipe for renewal or repairs and without detaching the sand pipe.

Another object of the invention is to provide a device of this character which may be applied without structural change to the 25 right or left hand side of the locomotive or other vehicle.

With these and other objects in view, the invention consists in certain novel features of construction as hereinafter shown and 30 described and then specifically pointed out in the claims, and in the drawings illustrative of the preferred embodiment of the invention—

Figure 1 is a side elevation of the improved device applied.

Fig. 2 is an enlarged vertical sectional elevation.

Fig. 3 is a side elevation of the upper part of the improved device, with the cover portion removed.

Figure 4 is a view of the electric resistance element detached and extended.

Fig. 5 is a plan view with the conductor wire sheathing in section on the line 4—4 of 45 Fig. 2.

The improved device comprises a tubular member 10 coupled to the sand conductor, indicated at 11, by a coupling member 12, the conductor adapted to be connected to the 50 sand dome, not shown, of a locomotive.

Surrounding the lower part of the tubular

member 10 is a tubular guard or "petticoat" 13, the latter provided with an inwardly directed stop flange 14 spaced from the lower end of the guard 13 and forming a guide 55 for the conductor member 10, the latter being threaded to receive a clamp nut 15 which binds against the flange 14, and thus holds the member 10 from upward movement. 60

Engaging around the tubular member 10 and bearing against the upper edge of the member 13 is a cap 16, the confronting edges of the parts 13 and 16 being "rabbeted" as 65 shown at 17, in Fig. 2.

Projecting from one side of the cap member 16 is a "housing" or casing 18 communicating at 19 with the interior of the cap and likewise provided with detachable closure 20. The housing 18 is provided with a 70 threaded aperture to receive a tubular sheathing 21 for electric conductor wires, as shown.

Extending from the upper portion of the guard member 13 are stop lugs 22 between 75 which the housing member 18 engages, to hold the cap and its housing in position either extending to the right or left, as required.

The device is disposed in an inclined position with the lower end bevelled as shown at 23 in Fig. 1, or in parallel relation to the rail, indicated at 24, and relatively close to one of the car wheels, a portion of which is represented at 25. By employing two sets 80 of the lugs 22, the device may be arranged upon either the right or left side of the locomotive by merely reversing the position of the cap 16, as will be obvious.

A clamp nut 26 is applied to the tubular 85 member 10 and bearing against the cap 16, as shown. The nuts 15 and 26 thus operate to firmly clamp the two parts 13 and 16 together.

At its lower end, the tubular conductor 10 90 is counter bored for a distance as shown at 27 to prevent moisture from passing upward into the conductor, as hereinafter explained.

The improved device is supported from 100 the framework of the locomotive or car in any suitable manner, for instance by a strap

28 encircling the member 13 and coupled at 29 to a standard 30 attached at 31 to a part of the framework indicated at 32.

The conductor 10 is surrounded by a non-conductive sheathing such as one or more layers of mica, indicated conventionally at 33, and the latter surrounded by another layer of non-conductive material such as mica and indicated at 34, the latter having 10 a coil of electrically conductive wire wound thereon and represented at 35 in Fig. 5, and capable of being heated by an electric current passed therethrough, and thus imparting heat to the conductor 13, and effectually preventing the accumulation of moisture therein.

The interior of the members 13 and 18 are lined with a suitable non-heat conductive element such as asbestos, and indicated conventionally at 36.

The nut 15 is provided with a suitable yieldable moisture proof packing indicated at 37, while a similar water proof packing 38 is disposed between the nut 26 and the 25 cap 16.

By this simple arrangement, the conductor tube 10 is heated to effectually prevent the accumulation of moisture therein, so the sand flows freely therethrough and is 30 thus prevented from being clogged by absorbing moisture, as will be obvious.

In rainy weather, the moisture gathers upon the outside of the parts 13 and 16 and is caused to flow around the lower edge of 35 the member 13 and thence upwardly by capillary attraction within the interior of the member 13, below the flange 14, but will be largely checked by the flange 14. The moisture will also be inclined to flow upwardly by capillary attraction within the conductor 10, but will not flow past the counterbore portion 27.

Moreover the heat imparted to the conductor member 10 above the counterbored 45 portion will effectually prevent the accumulation of moisture and cause the free flow of the sand.

The improved device is simple in construction, can be manufactured of any suitable 50 material and of any required size, and may be transposed from side to side of the locomotive or other vehicle by simply reversing the position of the cap member 16.

The preferred embodiment of the invention is disclosed in the drawings and set forth in the specification, but it will be understood that modifications within the scope 55 of the claims may be made in the construction without departing from the principle of the invention or sacrificing any of its advantages.

Having thus described the invention, what is claimed as new is:—

1. A device of the class described comprising a tubular conductor member adapted

to be coupled to a sand pipe, a tubular guard member enclosing a portion of said conductor member and with an inwardly directed bearing flange spaced from the lower end of the guard member and supporting 70 the conductor member, a cap member engaging around the conductor member and bearing upon the guard member, a housing extending from the cap member and communicating with the interior of the same 75 and adapted to contain an electrically conductive coupling device, an electrical heating appliance within the guard member and externally of the tubular conductor and adapted to be coupled to the electrical 80 coupling device within the housing.

2. A device of the class described comprising a tubular conductor member adapted to be coupled to a sand pipe, a tubular guard member enclosing a portion of said conductor member and extending below the line of the same, said guard member having an inwardly directed bearing flange spaced from the lower end of the guard member and supporting the conductor member, a 85 cap member forming a continuation of said guard member and engaging around the conductor member, and a heating appliance within the guard member and the cap and externally of the tubular conductor member. 90

3. A device of the class described comprising a tubular conductor member adapted to be coupled to a sand pipe and open at the lower end and counterbored at the open end, a tubular guard member enclosing a 100 portion of said conductor member and extending below the lower counterbored portion of the same, said guard member having an inwardly directed bearing flange spaced from the lower end of the guard member 105 and supporting the conductor member, a cap member forming a continuation of said body and engaging around the conductor member, and a heating appliance within the body and the cap and externally of the tubular conductor member. 110

4. A device of the class described comprising a tubular conductor member adapted to be coupled to a sand pipe, a tubular guard member enclosing a portion of said conductor member, a cap member engaging around the conductor member and bearing upon the guard member, a housing extending from the cap member and communicating with the interior of the same and 120 adapted to contain an electrically conductive coupling device, means for reversibly supporting said cap upon said tubular guard, and an electrical heating appliance within the guard member and externally of the tubular conductor and adapted to be 125 coupled to the electrical coupling device within the housing.

5. A device of the class described comprising a tubular conductor member adapted 130

to be coupled to a sand pipe, a tubular guard member enclosing a portion of said conductor member, means for supporting said guard member upon said conductor member, a cap member forming a continuation of said guard member and engaging around the conductor member, means for reversibly supporting said cap upon said tubular guard, and a heating appliance within the guard member and the cap and externally of the ¹⁰ tubular conductor member.

In testimony whereof, I affix my signature hereto.

CHILION BENJAMIN JOHNS.
